Primary Examiner — Catherine S Posthauer*(74) Attorney, Agent, or Firm* — Fitch Even Tabin & Flannery LLP(57) **CLAIM**

The ornamental design for a container lid, as shown and described.

DESCRIPTION

FIG. 1 is a top, front perspective view of a container lid, showing my new design;

FIG. 2 is a bottom, rear perspective view thereof;

FIG. 3 is a front elevation view thereof;

FIG. 4 is a rear elevation view thereof;

FIG. 5 is a first side elevation view thereof;

FIG. 6 is a second side elevation view thereof;

FIG. 7 is a top plan view thereof; and,

FIG. 8 is a bottom plan view thereof.

The broken lines depict unclaimed subject matter and form no part of the claimed design.
